11 Claims. (Cl. 259—4)

For storage of dense cellulosic pulp having a dry content of 12 to 20 percent it is common to use bins or towers which are filled from above and emptied at their bottom by flushing the pulp out. Flush water of a high pressure must be used which involves a high power consumption.

On the other hand, for mixing and equalization of pulp it is known to use circulation bins for pulp having a consistency of 3 to 4 percent. If such bins are to be used simultaneously for storage and mixing, they will be very extensive and costly and yet of merely a modest capacity on account of the low consistency of the pulp.

The present invention relates to a container suitable for storage as well as mixing of dense pulp, and also to a method of operating said storage container whereby an effective mixture and equalization of the pulp filling is obtained.

The essential feature of the method consists therein that the pulp, when charged, is spread over the container so that it is stored therein in superimposed horizontal layers, each of which extends at least over the greater part of the horizontal area of the container and contains pulp supplied approximately simultaneously, layers of various levels thus containing pulp supplied at different moments, and in that the pulp is discharged from the container by a vertical or inclined movement extending over the entire height of the pulp filling, so that pulp of the various horizontal layers is mixed into the discharged pulp. When the pulp is discharged by being flushed out with water, the water jets are directed vertically or obliquely downwardly in such a manner that the water works simultaneously or with short intervals against the various horizontal pulp layers and at an inclined free front thereof. The pulp mixture thus formed is flushed through bottom outlets out of the container. In order to spread the pulp across the container when supplied thereto there is used a charging device preferably arranged above the container and driven with a continuous uni-directional or reciprocating horizontal movement in such a manner that an orifice or similar thereon successively sweeps over the container in order uniformly to distribute the fed pulp over the area of the container, the movement being so rapid and so often repeated that at any spot the filling will be built up of a considerable number of superimposed thin layers, e.g. 10 to 50 layers. The flushing-out of the pulp which preferably is performed by using flush water of a pressure of 25 to 50 lbs. per sq. inch, is preferably effected by a flushing device comprising a pipe having one or more oscillating nozzles which are moved in parallel to themselves or are swung in a horizontal plane in a movement independent of the movement of the above-mentioned feeding device, possible on account of the flushing device being located in another horizontal plane than the feeding device.

The storage container according to the invention, in which the above-mentioned method of charging and discharging pulp can be practised, is essentially characterized by the provision of a charging device which is horizontally movable above the container for spreading of supplied pulp over the entire cross-sectional area of the container as thin horizontal layers, and by the provision of a device for flushing-out pulp which is likewise ar-

2

ranged above the container in order to be able simultaneously to flush pulp emanating from the various layers out through bottom outlets of the container, said flushing device being horizontally movable independently of the feeding device.

The invention will be more closely described herein below with reference to the accompanying drawing in which FIG. 1 shows a vertical cross-section of a preferred embodiment of the container, FIG. 2 shows a plan view thereof, and FIG. 3 shows a vertical cross-section taken along the cylindrical face indicated by the line I—I in FIG. 2.

The container shown in the drawing consists of an upright cylindrical outer wall 11, and a plane horizontal bottom 13. By means of a concentric inner wall 15 the container is divided into two separate compartments preferably having equally great base areas. Distributed over the bottom of the two compartments are outlet openings 17 grouped in radial rows. Each row of openings 17 is partly covered by a low, radially directed wall 19 which projects from the bottom at an acute angle. At least one of said walls of each compartment extends as a partition 21 (FIG. 3) up to the level of the upper edge of the walls 11, 15. In the base below the bottom 13 there are arranged two concentric collecting chambers 22, 23 which are provided with stirrers 25 and which, via conduits having shut-off valves 24 and 26, are alternately connectible to a conduit 29 for pulp discharged from the container, in which conduit a pump 27 is inserted.

The dense pulp to be stored in the container is supplied by a band conveyer 31 to a charging device comprising a conduit 33 arranged to swing in a horizontal plane above the container and which is pivoted on a pillar 35 located at the center of the container, the outer end of said conduit 33 being supported by a motor-driven carriage 37 running on the upper edge of the wall 11. Within the conduit there is a motor-driven screw conveyer 39 which takes care of pulp introduced into the conduit through a hopper 41 arranged at the inner end thereof and discharges said pulp through one or the other of two outlet openings 43, 45 arranged on the lower side of the conduit. The inner opening 43 can be covered by a shutter 47 when the pulp is desired to pass to the outer openings 45.

Located at a lower level than the above-described pulp charging device but yet above the container and pivotable in a horizontal plane is a flushing device comprising a horizontal flush water supply tube 51, attached to which are two nozzles 53, 55 which are pivotable in the vertical plane or in a steeply inclined plane, said plane being essentially parallel to the partition 21 (FIG. 3) when the flush water tube 51 is located approximately straight above said partition. The flush water tube 51 is pivoted on the central pillar 35 and is connected to a supply tube 57 for water of a relatively moderate pressure, said tube extending through the pillar. The outer end of the tube 51 is supported by a motor-driven carriage 59 which like the carriage 37 runs on the upper edge of the wall 11 but inwardly of the path of said last-mentioned carriage, so that the two carriages can pass each other unimpededly, the movement of the charging device thus being completely independent of the flushing device serving to discharge the pulp.

With respect of each of the compartments the charging device and the flushing device are active alternately, one being active when the other is inactive, and vice versa. However, the provision of two compartments enables simultaneous continuous pulp feed and continuous pulp discharge, pulp being charged into one compartment during intervals when pulp is discharged from the other, as shown in FIG. 1.

When filling the container with pulp the conduit 33

of the charging device is driven at such a speed that for each revolution merely a thin layer of pulp is laid off upon the earlier stored pulp. Thus the tube 33 must turn a great number of revolutions, e.g. 10 to 50 revolutions or more, in order to fill up the container completely. Therefore, in a vertical cross-section through the filled container an equally great number of layers of different storing ages can be discerned.

The discharge of pulp out of the filled compartment takes place by a flushing operation by means of the pivoting nozzles 53, 55 and starts with said nozzles in a position above the partition 21, so that a flow of diluted pulp can find its way along said partition to the outlet 17 without the risk of pulp dropping down and obstructing the open passage thus formed. Each of the nozzles 53 and 55 are preferably pivotally reciprocated radially with respect to the container compartments by motors 56 having eccentrically mounted output shafts 58 as illustrated in FIGURE 1. The flush tube 51 is rotated by a movement which is many times slower than the movement of the feed conduit 33 and which is determined exclusively by the desired pulp discharge rate. The water jets work the pulp along a free front thereof extending along the entire height of the pulp filling and will therefore carry with it and mix pulp particles emanating from all the various layers. The flush water dilutes the pulp to a consistency of e.g. approximately 3 percent, and the suspension flows through the next outlet 17 down into the collecting chamber 22 from where it is pumped further on. The outlets 17 may be permanently open, because stored pulp of a consistency of 12 to 20 percent is too solid to be able to pass therethrough by itself.

Within this scope of the invention modifications of the above-described embodiment are possible in various respects. Thus for instance, the container may be given a rectangular base area, the feeding device as well as the flushing device then preferably being arranged for a reciprocating rectilinear movement above the container.

I claim:

1. Method of storing and mixing cellulosic pulp in a container, consisting in spreading pulp supplied to the container for storage therein by displacing the point of supply of pulp horizontally over the container at a rapid rate, whereby pulp supplied within a short time interval is distributed over the entire bottom area of the container as a thin horizontal sheet, forming a great number of superimposed thin pulp layers by repeating said spreading operation, and discharging pulp from said container by means of flush water brought to flow in an inclined downwardly directed path across the pulp charge thereby bringing along and mixing pulp particles belonging to all of said layers into a suspension leaving the container.

2. In the storage of dense cellulosic pulp in and removal thereof from a storage container, a method for equalizing the properties of the pulp comprising: charging a first layer of pulp into the container, spreading said layer over at least the greater part of the horizontal area of the container, subsequently charging and spreading a plurality of superimposed horizontal layers of pulp onto said first layer one layer at a time so that each layer excepting the first layer contains pulp charged and spread subsequent to the pulp in the layer immediately below it; discharging the pulp from the container by serially removing a plurality of inclined increments pulp from the container, each increment extending over substantially the entire height of the first pulp layer and the pulp layers superimposed thereon so that each increment discharged contains pulp from each pulp layer.

3. Method as claimed in claim 2, characterized in that

the pulp is discharged from the container by flushing with at least one flush water jet which is directed obliquely downwards in such a manner that the water impinges simultaneously upon at least a majority of the horizontal layers of the pulp charge at a progressively moving point with respect to the layers so as to define an inclined free front thereof and flushes the pulp mixture thus formed out of the container.

4. Method as claimed in claim 2, characterized in that the pulp is spread from a moving pulp dispenser with generally horizontal movement in such a manner that the pulp dispenser successively sweeps over different parts of the container in order evenly to distribute the fed pulp over the entire area of the container, and in that the movement is that rapid and that often repeated that the charge will consist of 10 to 50 superimposed thin horizontal layers.

5. Method as claimed in claim 4, characterized in that the feeding step and the flushing step are repeated alternately.

6. Method as claimed in claim 4 wherein the rate of sweep of said moving pulp dispenser is substantially greater than the rate progressing movement of said flush water jet.

7. Storage container for cellulosic pulp comprising means defining container sidewalls and a container bottom; means defining an outlet in said bottom; a device for feeding pulp to the container, said device comprising a conduit having means defining at least one dispensing opening therein, said conduit being horizontally movable above the container in order to spread the pulp over the entire area of the container in the shape of thin horizontal layers, and a device for flushing pulp out of the container, which device likewise is arranged above the container in order to be able simultaneously to flush pulp emanating from the various layers out through said bottom outlet of the container, said flushing device being horizontally movable independently of the feed device.

8. Container as claimed in claim 7, characterized in that the container is cylindrical and that the feeding device and the flushing device are pivotable about an axis concentric to the container and arranged in different horizontal planes, so that they can move fully around and past each other without mutual interference.

9. Container as claimed in claim 7, characterized in that the flushing device comprises a horizontally movable flush water supply pipe, to which are attached a plurality of nozzles pivotable in steeply inclined planes.

10. Container as claimed in claim 8, characterized in that the container is divided up by means of radially extending partitions which are somewhat inclined to the vertical, bottom outlets being arranged in the bottom of the container close to each of said partitions and on the side thereof forming an acute angle to the bottom.

11. Container as claimed in claim 8, characterized in that the container is divided up by means of a cylindrical wall into an inner container and an outer annular container, and that the feeding device and the flushing device are adapted for work alternatingly in the inner and the outer container.
